UNITED STATES PATENT OFFICE.

ALFRED W. BUSH, OF CORONADO, CALIFORNIA.

FOUNTAIN-PEN CAP.

1,271,430.

Specification of Letters Patent.

Patented July 2, 1918.

Application filed March 8, 1918. Serial No. 221,255.

To all whom it may concern:

Be it known that I, ALFRED W. BUSH, a citizen of the United States, residing at Coronado, in the county of San Diego and State of California, have invented new and useful Improvements in Fountain-Pen Caps, of which the following is a specification.

The present invention comprehends improvements in fountain pens, and one so designed to facilitate a quantity of the pigment to be dispensed therefrom without necessitating the disconnection of the pen parts or elements.

To this end, the invention among other features contemplates the production of a plurality of pen elements serving as a conveyer for soluble or solidified ink and so constructed whereby the ink may be discharged therefrom when the filling of the pen is necessary or desired, without requiring the disconnection of the pen elements from one another.

A further object of the invention resides in the provision of means for manipulating and controlling the dispensing operation of the ink from the pen elements.

With the above and other objects in view the invention consists in the novel features, details of construction and combination of parts which will hereinafter be more fully set forth, illustrated in the accompanying drawing and pointed out in the appended claims.

In the drawing:

Fig. 1 is a side elevation of a fountain pen with a portion of the same shown in section;

Fig. 2 is a perspective view of the pen cap showing the parts thereof in disconnected position; and

Fig. 3 is a view similar to Fig. 1 illustrating the parts constituting the pen cap in open position;

Fig. 4 is a detail view showing the collar in locked position;

Fig. 5 is a perspective view illustrating the clip disconnected from the collar; and

Fig. 6 is a view similar to Fig. 4 showing the collar in a released position.

Referring more particularly to the accompanying drawing, wherein like characters of reference refer to corresponding parts in the several views, 5 denotes the fountain pen generally constructed of pen elements,

namely, the barrel portion thereof, denoted by the character 6, the pen nib 7 and the pen cap 8.

I aim in providing a pen structure embodying the above stated parts wherein a quantity of pigment in the nature of soluble ink tablets indicated by the character 9 may be stored and one so designed whereby a predetermined quantity of the pigment may be easily and expeditiously removed from the magazine portion of the cap, when desiring to refill the pen barrel, without annoyance or inconvenience to the operator of having to disconnect the magazine from the pen cap. Previous to describing the construction of these elements, I am desirous of having it understood, even though as here illustrated, the soluble ink is of tablet form, the same may, if desired, be of a powdered, pulverized or particle nature and capable of being dissolved and converted into ink by the contact of such with water or the like fluids.

Now referring to the pen cap 8, the element 10 thereof is of hollow tubular formation and into which the pen nib 7 is inserted when the use of the pen is not desired. Provided in the element 10 of the cap at a point adjacent the upper or meeting end 11 thereof is located a disk 12 providing the said end with an internally threaded socket 13 into which the lower or meeting threaded end 14 of the other element 15 of the pen cap is threaded for establishing a detachable connection of the pen elements with one another. For the sake of clearness, the pen element 15 will be hereinafter referred to as the magazine and into which the tablets 9 are stored. To facilitate the tablets to be dispensed from the magazine without requiring a disconnection thereof from the pen cap, I provide in the lower threaded end 14 of the magazine an opening 16 adapted to register with a similar opening 17 provided in the wall forming the socket 13 of the pen element 10, upon the screwing of the magazine into the socket 13 of the pen element 10. Loosely fitting around the meeting ends of the pen elements is an annular collar 18 having formed in the flange 19 thereof a substantially inverted U-shaped gate or slot 20, consequently upon the rotation of the collar upon the pen elements to a point for registering the slot 20 with the registering slots

16 and 17 of the respective pen elements 15 and 10, will permit of a quantity of the ink contained in the magazine to be dispensed therefrom, not only by obviating the necessity of disconnecting the pen elements from one another, but furthermore when the cap assumes a substantially perpendicular position. Provided in the flange 19 of the collar 18 to one side of its slot 20 is a stud 21 adapted to engage in the notches 22 provided in the side walls forming the slot 17 of the pen element 10, for limiting the movement of the collar 18 to a distance beyond the slots of the pen elements, consequently the operator will experience no difficulty in bringing the collar to a complete full open position or a complete full closed position.

The wall forming the internally threaded socket 13 is offset inwardly with respect to the plane of the element 10 to provide an annular shoulder 23 upon which the annular collar 18 loosely reposes. Consequently, upon the grasping of the finger 24 the collar 18 may be conveniently and expeditiously rotated upon the shoulder 23 as the occasion so demands. In practice, I have found it to be advantageous to lock the collar 18 against rotary movement, and to this end I provide in the base of the element 15 a recess 25 and a similarly constructed recess 26, the latter being provided in the upper edge of the annular collar 18 at a point to one side of the gate or U-shaped slot 20 thereof. Provided in the upper end of the finger 24 is a pair of superposed vertically aligned slots 27 through which project studs or the like fastening devices 28 for mounting the finger on the exterior circumference of the annular collar 18 for vertical sliding movement. Manifestly, upon the adjustment of the finger in an upward vertical direction and when the collar 18 assumes a closed position, the projection 29 provided on the extreme upper end of the finger engages in the recess 25 of the pen element 15 and establishes a locking action of the collar. When desiring to gain access to the pigment, the projection 29 is released from the recess 25 by sliding the finger 24 in a downward direction and to prevent any obstruction to the rotation of the collar 18 the projection 29 is brought to engage in the recess 26 of the collar, facilitating the release of the collar from the pen element 15. At this point, I am desirous of stating the finger 24 when the pen nib 7 is inserted in the pen element 10, may be utilized as a pen clip to prevent any accidental loss of the pen from the pocket of the wearer. From the foregoing description, taken in connection with the accompanying drawing, the advantages of construction and the method of operation will be readily apparent to those skilled in the art to which the invention relates, and while I have described

the principles of operation of the invention, together with the device which I now consider to be the best embodiment thereof, I desire to have it understood that the device shown is merely illustrative and that such changes may be made when desired as are within the scope of the appended claims.

What is claimed as new is:—

1. In a fountain pen, the combination with a pen barrel, a sectional ink conveyer detachably connected therewith, and means embracing the sections at their juncture for permitting a quantity of the ink to be dispensed from the conveyer without disconnecting the latter from said barrel.

2. In a fountain pen, the combination with a pen, a sectional ink conveyer therefor and the sections of the conveyer each being provided at their juncture with openings, and means defined between the juncture ends of the conveyer for controlling the dispensing operation of a quantity of ink from the conveyer, and means for manipulating said latter mentioned means.

3. In a fountain pen, the combination with a pen barrel, a sectional member adapted to contain a quantity of ink detachably connected with the pen barrel and each provided with an opening, the opening of one section registering with the opening of the other section upon the connected position of said sections, and means for controlling the dispensing of the ink through the registering openings of the sections.

4. In a fountain pen, the combination with a pen barrel, of a magazine having a dispensing opening detachably connected with the pen barrel and adapted to contain a quantity of ink and a collar loosely embracing the magazine for controlling the dispensing operation of the ink through the opening thereof.

5. In a fountain pen, the combination with a pen barrel, an ink conveyer detachably connected therewith and provided with a dispensing opening, a member loosely embracing the conveyer for controlling the dispensing operation of the ink from the dispensing member without disconnection of the latter from said barrel, and means for locking the latter mentioned means against retrograde movement.

6. In a fountain pen, the combination with a pen barrel, an ink conveyer detachably connected therewith and provided with a dispensing opening, a member loosely embracing the conveyer for controlling the dispensing operation of the ink from the dispensing member without disconnection of the latter from said barrel, means for locking the latter mentioned means against retrograde movement, and means slidably mounted on the latter mentioned means for locking the former against any accidental retrograde movement.

7. In a fountain pen, the combination with a pen barrel, an ink conveyer detachably connected therewith and provided with a dispensing opening and a recess, a member
5 loosely embracing the conveyer for controlling the dispensing operation of the ink from the dispensing member, and means slidably mounted upon the latter mentioned means for engagement in the recess of the ink conveyer for locking the member against any 10 accidental retrograde movement.

In testimony whereof I affix my signature.

ALFRED W. BUSH.
